Inventor:

Frank Dochnal.

By *Frank Dochnal*
Attorney.

UNITED STATES PATENT OFFICE.

FRANK DOCHNAL, OF ST. LOUIS, MISSOURI.

TILE FOR WALL STRUCTURES.

1,277,556.

Specification of Letters Patent. Patented Sept. 3, 1918.

Application filed April 26, 1917. Serial No. 164,599.

To all whom it may concern:

Be it known that I, FRANK DOCHNAL, a citizen of the United States, residing in the city of St. Louis, State of Missouri, have 5 invented certain new and useful Improvements in a Tile for Wall Structures, the same forming a continuation in part of my application for United States Letters Patent, filed April 17th, 1916, Serial No. 10 91,530, and of which the following is a specification.

My present invention relates to an endless and interlocking tile wall structure as a whole, and more particularly to a tile from 15 which the wall may be formed.

The object of my invention is to provide a specially constructed hollow tile which can be easily made and which will be strong, durable and easily placed into a wall structure either of a reinforced or a non-reinforced type.

A further object of the invention is to so construct the hollow tile that when the same is filled with a cementitious material, 25 the inner and outer wall thereof will be firmly united, also that the adjacent tile in the contiguous course will be anchored or united together end for end in an endless solid wall.

30 A further object of the invention is to provide the upper face of the central cross wall and the end walls upon one side of the longitudinal center of the tile with a reinforcing rod receiving recess.

35 With the above and other objects in view my invention consists in the novel construction of a tile hereinafter described, illustrated and finally pointed out in the claims appended.

40 To carry out the aim of my present invention to the best possible advantage I employ a particular form of this tile, as illustrated in the drawings, and set out in the appended claims.

45 Referring to the accompanying drawings forming a part of this specification wherein like characters of reference denote similar parts throughout the several views:

Figure 1 is a perspective view of a straight 50 wall constructed of tile made in accordance with my invention. The wall being shown partly as a hollow wall and partly as a solid wall.

Fig. 2 is a perspective view of a tile constructed in accordance with my invention.

Fig. 3 is a detail partly in vertical sec-

tion and partly in full lines of a pair of tile provided with a horizontal and a vertical reinforcing rod embedded in cement.

Fig. 4 is a plan view of a circular wall 60 construction formed of tile made in accordance with my invention. A portion of this wall being shown as a hollow wall and the remainder as a solid wall.

Fig. 5 is a modified form of tile employing 65 only one rib on each side of the center cross-wall instead of two, as shown in Fig. 2, and which rib on each side of the center cross wall in this modified form carries out the same function as two ribs formed on 70 either side of the center cross-wall.

The walls as shown in Figs. 1 and 3 of the drawing are formed by my improved type of tile including the cementitious filling and the reinforcing rods. The tile are 75 arranged in the usual contiguous courses to break joints with the tile of the adjacent courses.

In carrying out the aim of my invention I employ a specially constructed tile and for 80 this purpose it is constructed as follows:

The tile consists of two walls 1 and 1'. Either wall may be used as the inner or outer wall although wall 1' is preferably used and laid so as to form the outer wall. 85 The walls 1 and 1' are connected by means of a centrally arranged and transversely disposed cross-wall 2. The cross-wall 2 is provided on each face with a pair of suitably spaced vertically disposed and longitudinally extending ribs 3 and 3'. These ribs, 90 it will be observed, are preferably arranged in opposed pairs. The side walls 1 and 1' terminate at each end in the inwardly projecting end wall 4 and 4' respectively, which 95 walls 4 and 4' in turn terminate in longitudinally disposed ribs 5 and 5' respectively, which ribs are preferably in alinement with the ribs 3 and 3' respectively, as clearly shown in Fig. 2. A passage 6 is formed be-

tween the free ends of each pair of ribs 3 and 5 and 3' and 5' which passages communicate on one side with the side pockets 7 and upon the opposite side with the centrally disposed pockets 8 formed between 100 the inner faces of the ribs 3 and 3' and the ribs 5 and 5'. These pockets are formed on each side of the central cross-wall 2, as clearly shown in Fig. 2. The pockets 8 it will be observed have the open ends 9. The 110 ribs, pockets and passages are all preferably vertically disposed, as illustrated.

The center cross-wall 2 and the end walls 4' are each provided with a concaved reinforcing rod receiving recess 10. It will be observed that the upper end of each web 3' and 5' as well as the cross wall 2 and the upper end of each wall 4' form the bases of the recesses 10. The object of these recesses, which are formed in the upper face of the cross-walls of the tile and to one side of the longitudinal center thereof, is to provide a channel and supporting means for a horizontal reinforcing element 11. The inner wall of the recess 10 formed in the upper face of the central cross wall 2 acts as a stop for the reinforcing rod 11 thereby preventing extreme lateral movement of the reinforcing rod 11 at the middle portion of each tile from any cause or undue strain applied to the reinforcing rod 20 while constructing a wall.

Having reinforcing element 11 positioned upon one side of the longitudinal center, and upon the upper face of the tile, permits the reinforcing rods 12 to be positioned 25 along the longitudinal center line of the tile instead of to one side thereof, thus adding greater strength to the wall against wind pressure, while the offset horizontal reinforcing element 11 binds the outer half 30 of the wall together. This reinforcing element 11 is preferably positioned in this offset position to overcome defects caused by contraction and expansion of the outer half of the wall.

35 In building a circular wall structure, as shown in Fig. 4, for use, for instance, as silo or stack purposes the inside wall, it will be observed, is concaved at 13 and the outer wall is convexed as at 14. The end walls 40 4 and 4' are converging as clearly shown.

When the tile is used in stack, silo, or similar circular wall construction, it will be observed that I employ a split circular reinforcing rod 11 in combination with one 45 or more vertical reinforcing rods 12 placed upwardly through each or each alternate tile.

By referring to that portion of the wall which is shown as solid due to the use of 50 the cementitious filling 15, it will be understood, that the side walls 1 and 1' are firmly anchored or united by means of the cementitious filling deposited in the pockets 7 and 8 and the passages 6 of the tile and that due 55 to this filling it is impossible for any part or parts of the side walls to fall out should they break for any reason after the filling has set in the pockets and passages, which breaking may be due to any of many causes 60 such for instance as expansion or contraction of the materials used in the wall structure. It will be further observed that the ribs 3 and 3' or their equivalents on either side of the center cross-wall 2 firmly unite 65 the cementitious filling on each side of the

center cross-wall 2 by adhering to the face of the wall 2 and to the faces of the ribs 3 and 3' or their equivalents.

I have shown in Fig. 5 of the drawing a slight modification in the formation of the 70 ribs formed on the center cross-wall 2 of the tile. I have shown the center cross-wall 2 in this instance provided with a single rib 16 preferably of a width equal to the combined width of the ribs 5, 5' and pockets 75 8. In small tile structures, however, these ribs 16, may be of less width than that shown if found necessary or desired. One rib, in this instance, is formed on each side of the center cross-wall 2 instead of 80 two suitably spaced ribs 3 and 3', as shown in Fig. 2 of the drawing.

It is obvious from the foregoing description and the illustrations, that I have formed a tile which when laid to form a 85 wall structure, will be practical, strong and easily laid when used together with horizontal and vertical reinforcing rods, or with either reinforcement alone or without reinforcement whatsoever, excepting the cementitious filling.

I am aware that minor slight changes may be made in the specific form or location of the several ribs employed in my improved form of tile, hence, I reserve the right to 95 make any such changes or modifications in the formation or location of these ribs as may fairly fall within the scope of the appended claims without departing from the spirit or scope of my invention.

What I claim is:

1. A tile comprising an inner and outer wall, a central cross-wall uniting said inner and outer walls, a pair of suitably spaced ribs formed at each side of said central 105 cross-wall, a short end wall formed at each end of said inner and outer walls and terminating in an inwardly projecting rib.

2. A tile comprising an inner and outer wall, a central cross-wall uniting said inner and outer walls, a pair of suitably spaced ribs formed at each side of said central cross-wall, a short end wall formed at each end of said inner and outer walls and terminating in an inwardly projecting rib, 110 said ribs and walls adapted to form a plurality of pockets on each side of said central cross-wall, 115

3. A tile comprising an inner and outer wall, a central cross-wall uniting said inner and outer walls, a pair of suitably spaced ribs formed on each side of said central cross-wall, a short end wall formed at each end of said inner and outer walls and terminating in an inwardly projecting rib, said 120 ribs and walls adapted to form a plurality of pockets on each side of said central cross-wall, the pockets on each side of said central cross-wall adapted to communicate with each other.

4. A tile comprising an inner and outer wall, a central cross-wall uniting said inner and outer walls, a pair of suitably spaced ribs formed on each side of said central cross-wall, a short end wall formed at each end of said inner and outer walls and terminating in an inwardly projecting rib, said ribs and walls adapted to form a central pocket having an open end on each side of said central cross-wall, and a pair of side pockets formed on each side of said central cross-wall adapted to communicate with said central pockets.

5. A tile comprising an inner and outer wall, a central cross wall uniting said inner and outer wall having its upper face provided with a recess adapted to receive a horizontally disposed reinforcing rod to prevent extreme inward lateral movement thereof, a pair of suitably spaced ribs on

each side of said central cross wall, a short end wall formed at each end of said inner and outer wall and terminating in an inwardly projecting rib.

6. A tile comprising an inner and outer wall, a central cross wall uniting said inner and outer wall, means formed on the upper face of said central cross wall adapted to act as a stop for a horizontally disposed reinforcing rod and prevent inward lateral movement thereof at the middle portion of the tile, a pair of suitably spaced ribs formed on each side of said central cross wall, a short end wall formed at each end of said inner and outer wall and terminating in an inwardly projecting rib.

In testimony whereof, I have hereunto signed my name to the specification.

FRANK DOCHNAL.
